(57) CLAIM

The ornamental design for a hotel rooftop, as shown and described.

DESCRIPTION

FIG. 1 is front perspective view of the hotel rooftop showing my new design; and,

FIG. 2 is a rear perspective view thereof.

The fragmentary contour lines depict travertine veining on the claimed surfaces.

The broken lines in the drawings depict portions of the hotel rooftop that form no part of the claimed design.

The drawings contain a dot-dash symbolic break, given the impracticability of showing the entire rooftop in a single view. The claim is directed to the overall appearance of all the elements claimed cumulatively in the figures.
